HOISTING APPARATUS.

1,026,901.

Specification of Letters Patent.

Patented May 21, 1912.

Application filed August 28, 1911. Serial No. 646,430.

To all whom it may concern:

Be it known that I, EUGENE BROWN, a citizen of the United States, residing at Colfax, in the county of Whitman and State 5 of Washington, have invented a new and useful Hoisting Apparatus, of which the following is a specification.

This invention has reference to improvements in hoisting apparatus and is designed 10 more particularly to provide a hoisting apparatus which may be attached to the frame of a wagon whereby heavy articles are readily lifted into and deposited on the wagon, the hoisting apparatus being attached to 15 and detached from the wagon in whole or in part with the greatest facility.

The present invention is especially adapted 20 for the handling of grain which in the far western portion of the United States is threshed out in the field and deposited on the ground in bags holding approximately two bushels each and weighing from one hundred and thirty to one hundred and forty pounds apiece. It is customary to 25 load the bagged grain into wagons and so carry the grain to the point of shipment instead of storing the loose grain in granaries or elevators. The lifting of such bags of grain from the ground into the wagon usually 30 takes the labor of two men and is an exhausting labor, and if attempted by one man alone is too exhausting to be kept up for any length of time. Heretofore no device has been available for the ready lifting 35 and deposition of the bags of grain in the wagons by which the grain was transported to the shipping point. For such purpose the present invention provides a crane and a support therefor which may be attached 40 to the side of a wagon frame with the greatest ease and with the aid of such tools as are customarily found on a farm.

To keep the cost of production of the 45 structure of the present invention, and consequently the price at which it may be sold to those needing such devices, within reasonable limits, the structure is made of as few parts as may be and such parts in the main as can be bought in the open market. Furthermore, the device is constructed in a manner 50 to permit the handling of such bags of grain as have been mentioned, or like weights, by a single man or boy as expeditiously as they can be handled in the ordinary manner by two men, and the structure

of the hoisting device permits its partial dismantling when the wagon is being moved over considerable distances, so that the parts are not in the way, or substantially the whole structure may be removed from the wagon 60 when it is not desirable to transport it.

The invention will be best understood from a consideration of the following detailed description, taken in connection with the accompanying drawings forming a part 65 of this specification, with the understanding, however, that while the showing of the drawings is of a practical form of the invention the latter is by no means limited to strict conformity with such showing of the 70 drawings, for it is susceptible of various changes and modifications so long as the salient features of the invention are retained.

In the drawings:—Figure 1 is a perspective view of the invention as applied to a wagon. Fig. 2 is a section on the line 2—2 of Fig. 1 but drawn to a larger scale. Fig. 3 is an elevation of the upper end of the crane omitted from Fig. 2 but drawn to the 75 same scale. Fig. 4 is a diametric section through the windlass structure in the line of the longitudinal axis thereof, some parts being shown in elevation, but drawn to a larger scale than Figs. 1, 2 and 3. Fig. 5 80 is a section on the line 5—5 of Fig. 4 and showing the back stop pawl in position. Fig. 6 is a section similar to Fig. 5 but with the outer ratchet wheel broken away and showing the inner pawl in a position sub- 85 stantially diametric to that of Fig. 5. Fig. 70

Referring to the drawings, there is shown in Fig. 1 a wagon 1 which may be taken as typical of any suitable structure for the purpose, and which is designed to receive a load, 95 such, for instance, as bags 2 of grain, as already referred to. To a side bar 3 of the wagon on the under side thereof, considering the wagon in ordinary position, there is secured a strip 4 preferably of angle steel, 100 and this strip is made fast to the bar 3 by screws 5 or otherwise. Approximately midway of the length of the strip 4 the bar 3 has fast thereto a bracket 6 with a terminal portion 7 projecting in a substantially horizontal direction beyond the front face of the bar 3, the bracket 6 being made fast to the rear face of the bar 3 by screws 8 or in any other appropriate manner. These two parts just described are the only parts of the whole 105 110 115

structure made directly fast to the wagon and as screws or bolts are used for such purpose even these two parts may be readily detached, although ordinarily this is not done, for the parts are not usually in the way.

There is provided a frame made up of side members 9 and end members 10 all preferably of angle steel and riveted or otherwise secured together and provided with an intermediate brace member 11 approximately parallel with the end members 10 but spaced therefrom, being nearer to the upper end member 10 than the lower end member 10, the terms of position being with respect to the parts when in normal working position. The side members 9 of the frame carry angle clips or brackets 12 made fast to the frame members by bolts 13 or in any other appropriate manner, and each bracket 12 has an angle extension 14 parallel with but spaced from the corresponding side member 9, so that the side members 9 may rest against the outer face of a wagon side bar 3 with the angle portion 14 of the bracket 12 engaging the inner face of said bar, thereby holding the frame to the bar. The bolts 13 may carry between the bracket 12 and the corresponding face of the respective side member 9 washers 15 to accommodate the structure to wagons having side bars 3 of different thicknesses. The frame made up of the members 9, 10 and 11 also carries a strap 16 having approximately right angle extensions 17 at the ends, and these extensions are riveted or bolted to the side members 9, so that the strap 16 is opposite the brace member 11 in spaced relation thereto and on the opposite face of the frame from said brace member. Moreover, the strap 16 is held to the frame by braces 18 in a manner to render the strap 16 rigid with relation to the frame.

Near one end of the frame, such end being the one more distant from the strap member 16, are latch levers 19, each lever being of the first order and having its longer arm bent into an approximate right angle, while the shorter arm terminates in a toe 20 projecting from said shorter arm of the lever in a direction opposite from the direction of the angle portion of the longer arm. When the frame is placed on the bar 3 the toe 20 may be engaged behind the depending web of the angle strip 4, the latter being attached to the bar 3 so that one web will depend therefrom substantially flush with the outer face of the bar 3. In this manner the frame made up of the members 9 and 10 and the parts carried thereby may be locked to the bar 3 as firmly as necessary for the purposes of the invention by the latch levers 19 but by properly manipulating the longer arms of the levers the frame is readily unlatched and lifted from the bar 3.

However, it is desirable that the frame be positively locked against accidental displacement from shocks and jars to which the wagon may be subjected when being drawn over a field upon which the bags of grain are deposited. For this purpose the two levers 19 have their longer arms joined by a strip 21 and this strip is provided with a longitudinal slot 22 in such position as to be traversed by the end 7 of the bracket 6 when the latch levers are in the locking position, and the said end 7 is perforated for the passage of a pin 23 which may be held fast to the strip 21 by a chain 24 or otherwise to prevent the pin from being lost. When the bracket end 7 is in traversing relation to the strip 21 and the pin 23 is in place, the latch levers cannot move to the unlatched position and the frame is therefore locked against accidental displacement on the bar 3, but whenever it is desirable to remove the frame it is only necessary to withdraw the pin 23 and by grasping the strip 21 move both levers simultaneously to the unlatched position, whereupon the frame made up of the members 9 and 10 and other parts carried thereby may be readily lifted from the bar 3.

The lower end member 10 carries about midway of its length a step bearing 25 and the upper bar 10 about midway of its length carries a journal bearing 26, the end member 10 having a passage therethrough coincident with the bearing 26 for the upright member of a crane 27, the lower end of the upright member having a bearing in the step 25 and transversing the bearing 26. The crane is provided with an angle or overhanging arm 28 at approximately right angles to the upright member, as is customary in cranes, and this arm 28 is strengthened by an angle brace 29 made fast at one end to a collar 30 on the upright member of the crane immediately above the bearing 26, and at an appropriate point on the arm 28 of the crane the brace 29 has a collar 31 made fast by a rivet 32 or otherwise. The upright member of the crane and the overhang member may both be made of pipe and the two parts joined together by an ordinary elbow coupling. The brace 29 may also be made of piping.

The intermediate member 11 at one side of the upright portion 27 of the crane carries a bearing 33 and the strap 16 carries a similar bearing 34 in line with the bearing 33 and both the member 11 and the strap 16 have passages therethrough in line with the respective bearings for a shaft 35, one end of which extends through the member 11 and beyond the same has a retaining nut 36 applied thereto with an intermediate washer 37. The other end of the shaft 35 extends beyond the corresponding end of the bearing 34 and there receives a manipulating

crank 38 held to the shaft by a pin 39, which latter may be a cotter pin and may be made fast to the crank against accidental loss by a chain 40.

5 Mounted on the shaft 35 is a drum 41 with end flanges 42, 43, respectively, the end flanges 43 being of greater diameter than the flange 42 and formed on the periphery with a circular series of ratchet teeth 44 to be engaged by a pawl 45 pivoted to a holder 46 in turn made fast to the adjacent side member 9 of the frame. The drum is hollow and open at one end, while the other end is closed by a web 46 joining a hub 47 traversed by the shaft 35, but the hub 47 is not made directly fast to the shaft and under circumstances to be described may turn freely on the shaft. Mounted on the shaft 35 between the hub 47 and the strap 20 16 is a collar 48 made fast to the hub by a pin 49 traversing the collar and shaft. Formed on one end of the collar 48 is a radially extending ear 50 in turn carrying a pawl 51. Within the drum 41 adjacent the web 46 is an annular series of inwardly directed teeth 52 and these teeth and the pawl 51 are shaped for engagement one with the other, but the relation of the teeth to the pawl and its carrying ear 50 is such that the 25 pawl may move away from and out of engagement with the teeth or may move into engagement with the teeth under circumstances to be described. Made fast to the drum for winding thereon is a rope or strand 53 of any suitable material, such as flexible wire rope and this rope is carried about a pulley 54 mounted in an angle bracket 55 made fast to the upright member 27 of the crane and the overhanging arm 30 40 thereof adjacent the connection between these two members, and from thence the rope is carried to another pulley 56 supported by a bracket 57 made fast to the outer end of the overhanging arm of the crane. The rope 53 is carried from the pulley 56 over another pulley 58 and the end of the rope is made fast by a ring 59 to the bracket 57. The pulley 58 carries a pair of 45 50 lifting tongs 60 which may be made of angle metal and be appropriately shaped to grasp a filled bag 2 without injury to the latter, or these tongs may be replaced by other grasping means adapted to the particular form of the material to be lifted. Of 55 course, the pulley 54 may be differently located so that the rope or cable will follow a different path from the windlass to the pulley 56, as these are matters which may be varied within quite wide limits and do not 60 affect the general operation of the device.

The brackets or clips 12 are made adjustable lengthwise of the members 9, as well as to and from them, the lengthwise adjustment being accomplished by providing 65 elongated slots in the clips 12 for the bolts

13, and the device is, therefore, readily adapted to wagons where the side bars 3 may vary in width and thickness. The crane is attached to either side of the wagon as may be desired.

70

Suppose, now, that it is desired to gather up sacks of grain which have been left by the harvesting machinery on the field, so that such sacks of grain may be carried to the point of shipment. The wagon is driven 75 to the appropriate point, the crane is swung outwardly from the wagon, this being permitted by the bearings 25 and 26, and the tongs 60 are drawn downwardly until they may be caused to embrace a sack of grain. 80 The drawing down of the tongs necessitates the unwinding of the cable 53 from the drum 41 which is permitted by the lifting of the back stop pawl 45. Under ordinary circumstances when there is no load on the 85 crane the handle 38 will gravitate to the pendent position and in this condition the ear 50 with its pawl 51 is uppermost and the pawl 51 will fall until in engagement with the collar 48, such position being 90 shown in Fig. 5. The drum is thereby disconnected from the shaft 35 and may freely rotate under the weight of the tongs or because of a slight force applied to the tongs tending to unwind the cable 53 from the 95 drum, and there is no danger of the pawl 51 engaging the teeth 52 under such circumstances. In order to lift the engaged sack, the operator grasps the crank and turns it. For a portion of a turn the crank is inactive, but as soon as the ear 50 is moved to the lower position the pawl 51 becomes pendent and drops into engagement with one 100 of the teeth 52, and thereafter as force is applied to the crank the drum 49 participates in the rotative movement of the crank, the pawl 51 being held against accidental escape from the teeth 52 by the applied pressure, and so long as rotative movement is applied to the crank the drum will turn 105 110 and wind the cable 53 thereon and through the tackle provided will cause the lifting of the sack, which may be accomplished by a single person, even of comparatively little strength, because of the multiplying effect 115 of the tackle. When the sack has been raised to the desired height it will be there held by the back stop pawl 45 and the crane may be swung around until the sack is over the body of the wagon, when the crank may 120 be again grasped and by releasing the drum from the back stop pawl 45 the sack may be gradually lowered on to the wagon. The sack is now released from the tongs and the crane may be swung to the first position, 125 after which the tongs may be grasped and pulled to the lowered position, the crank 38 escaping from engagement with the drum as soon as the crank reaches substantially the pendent position, so that there is no whirl- 130

ing crank to possibly injure the operator and also to add its resistance to the ready lowering of the tongs.

It is not advisable to have the winding drum rotate too freely, especially when the rope is being unwound therefrom, and for this reason there is provided a flat spring 61 carried by the strap 16 and bearing against the corresponding end face of the drum 41 to thereby provide a moderate frictional resistance to the rotation of the drum, so that it will not rotate unless there be some force applied to the tongs. This avoids any liability of the cable 53 becoming unwound from the drum to too great an extent and thereby becoming tangled.

When the load on the wagon is completed, or all the sacks in a neighborhood have been gathered, the handle is readily disconnected from the shaft and the crane may be swung over the wagon out of the way or if it be desirable to use the crane upon other wagons in the field while the loaded wagon is being driven to the point of shipment, the whole structure is very readily removed from the wagon by simply manipulating the latch levers 19 to unlatched relation with the strip 4 when the entire crane structure may be lifted from the wagon frame bar 3 and be applied to another wagon to be locked thereto in the manner already described.

While the foregoing description has been confined largely to a structure particularly adapted for hoisting sacks of grain into wagons, it will be understood that by changes in the form of the tongs, or even without changes in the tongs the device may be employed for hoisting other things than sacks of grain into wagons and may be utilized in other connections, but the device is designed more particularly for the specific purpose described, and is especially adapted for such work, and the facility with which the device may be attached to or removed from wagon frames of ordinary structure greatly enhances the value of the invention.

What is claimed is:—

1. A hoisting attachment for vehicles comprising a crane, a windlass therefor, and a supporting frame for the crane and windlass having clips for engaging a wagon frame, and latches carried by the supporting frame in position to engage the wagon frame and coacting with the clips for locking the supporting means for the crane to the wagon frame.

2. In a hoisting attachment for wagons, a crane and windlass therefor, and a support for the crane and windlass comprising a frame having bearings for the crane and for the windlass, wagon engaging clips carried by the frame, and latch levers also carried

by the frame in position to engage the wagon in locking relation to the clips.

3. In a hoisting attachment for wagons, a crane and windlass therefor, and a support for the crane and windlass comprising a frame having bearings for the crane and for the windlass, wagon engaging clips carried by the frame, and latch levers also carried by the frame to engage the wagon in locking relation to the clips, said latch levers being in spaced relation one to the other and each in coactive relation to a respective clip.

4. In a hoisting attachment for wagons, a crane and a windlass therefor and a supporting frame for the crane and windlass comprising side and end members, the end members carrying bearings for the crane and the side members carrying bearings for the windlass, clips carried by the side members for engagement with a portion of the wagon body, latch levers carried by the side members in opposition to the clips and each in coöperative relation to a respective clip, said levers being connected by a junction bar for simultaneous movement, and a bracket or stirrup adapted to be made fast to the wagon body, the junction bar for the latch levers having a passage therethrough for the stirrup and the latter being provided with means for securing the junction bar thereto.

5. In a hoisting attachment for wagons, a crane, and a windlass therefor, a supporting frame for the crane composed of side and end members and an intermediate member joining the side members, another member spaced from the intermediate member and connected to the side members, said intermediate members being provided with bearings for the windlass and the end members being provided with bearings for the crane, adjustable clips on the side members for engagement with the wagon frame, latch levers carried by the side members in co-operative relation to the clips, a slotted junction strip for the levers, and a bracket or stirrup adapted to be secured to the wagon frame in position to extend through the slot in the junction bar of the latch levers when the levers are in latching engagement with the wagon frame, and means for connecting the junction strip to the stirrup when the latter is in traversing relation to the slot in said junction strip.

In testimony, that I claim the foregoing as my own, I have hereto affixed my signature in the presence of two witnesses.

EUGENE BROWN.
